EXPANSION VALVE

**Earnest J. Dillman, Detroit, Mich., assignor to
Detroit Lubricator Company, Detroit, Mich., a
corporation of Michigan**

Application February 1, 1943, Serial No. 474,301

1 Claim. (Cl. 236—92)

This invention relates to new and useful improvements in valves for controlling the flow of refrigerant medium to an evaporator.

An object of the invention is to provide a valve which will operate efficiently at extremely low temperatures.

Another object is to provide a valve in which the single temperature and back pressure responsive element has a substantially frictionless connection with the valve member.

Another object is to provide in a low temperature valve having a single temperature and back pressure operating element, means to prevent contact of the refrigerant medium with the element.

Another object is to provide an expansion valve having a novel external equalizer connection.

The invention consists in the improved construction and combination of parts to be more fully described hereinafter and the novelty of which will be particularly pointed out and distinctly claimed.

In the accompanying drawing to be taken as a part of this specification there is fully and clearly illustrated a preferred embodiment of the invention, in which drawing:

Fig. 1 is a diagrammatic view of a refrigerating apparatus including the valve of the invention;

Fig. 2 is a detail view partly in section of the valve on the line 2—2 of Fig. 1, and

Fig. 3 is a view of the valve in longitudinal central section on the line 3—3 of Fig. 2.

Referring to the drawing by characters of reference, 1 designates generally a compressor driven by a motor or the like, not shown, and controlled in any suitable manner. The outlet of the compressor is connected by a conduit 2 to a condenser 3 from which a conduit 4 leads to the inlet 5 of the expansion valve 6. From the expansion valve outlet 7 a conduit 8 leads to the refrigerant medium evaporator 9 which is connected by a conduit 10 to the inlet of the compressor 1. The suction or return line conduit 10 has clamped thereto, adjacent the outlet of the evaporator, the feeler element or bulb 11 of the thermostatic power element for the valve 6. The external equalizer of the valve 6 is connected by a pipe 12 to the suction conduit 10 at a fitting 13 adjacent the evaporator outlet.

The valve 6 has a body or casing 14 with an inlet conduit 15 for connection to the condenser 3 by the conduit 4. The conduit 15 leads through a warm liquid refrigerant chamber 16 and pas-

sageways 17 into the chamber 18. Within the chamber 18 there is a valve member 19 cooperable with a valve seat member 20 and carried by a supporting member 21 which is urged in valve closing direction by an adjustable spring 22 supported and held under compression by an adjustable follower member 23. A suitably packed adjustment screw 24 is carried by the body 14 and supports the follower member 23. The valve member 19 controls flow of refrigerant medium into the outlet conduit 25 which is connected to the conduit 8 leading to the evaporator 9. The chamber 16 is closed by a partition member 26 sealed to the casing 14 and recessed to provide a back pressure chamber 27. Mounted on the body member 14 and sealed to the partition member 26, there is a recessed cap member 28 forming part of the valve operating fluid thermostat or power element and containing an expansion chamber 29. The chamber 29 is separated from the back pressure chamber 27 by a pressure responsive diaphragm member 30, which is hermetically sealed at its periphery to the partition member 26 and cap member 28. Within the cap member 28 there is a helical coil compression spring 31 acting on the diaphragm member 30 and urging it toward the partition member 26. The chamber 29 is connected by a capillary tube 32 to the feeler member 11. The fluid thermostat 30 is a gas charged type power element having a limited quantity of volatile liquid, preferably the same as the refrigerant medium used in the refrigerating apparatus, the quantity being such that all of the liquid can condense within the chamber 29.

The back pressure chamber 27 is connected by a passageway 33 to the portion of the outlet conduit 25 which is aligned with the valve port formed by the seat member 20. Loosely guided in the passageway 33, as at 34, there is a force transmitting thrust member or push rod 35 which extends into the back pressure chamber 27 for operative abutting engagement with the diaphragm member 30 and which has its other end 45 extending through the valve port for operative abutting engagement, as at 36, with the valve member 19. The passageway 33 is enlarged, as at 37, to provide a draw-off chamber having an apertured end wall 38 surrounding the thrust member 35 and separating the chamber 37 from the outlet conduit 25. The aperture through the wall 38 is sufficiently large so that the thrust member can have free lateral movement. Within the chamber 37 there is a sleeve member 39

having a close sliding fit on the thrust member 35 and seating on the end wall 38 to close the aperture therethrough, the member 39 being laterally shiftable in the chamber 37 to accommodate lateral movement of the thrust member 35. Within the chamber 37 there is a helical coil spring 40 which surrounds the thrust member 35 and is held under compression between the chamber upper end wall and the sleeve member 39 to hold the sleeve member 39 tightly against the end wall 38. Opening into the draw-off chamber 37 is the external equalizer connection passageway 41 provided with a screw-threaded outlet 42 which opens through the outer wall of the casing 14 for connection of the pipe 12 to the suction conduit 10.

The operation of the valve is as follows. When the compressor 1 is placed in operation, the refrigerant back pressure is reduced and is transmitted through the pipe 12 and passageway 41 to the chamber 37, the loose fit of the thrust member in the guide portion 34 resulting in reduction of pressure in the back pressure chamber 27. Since the evaporator 9 is warm the reduction of pressure will permit the pressure of the power element in chamber 29 to move the diaphragm member 30 downward to open the valve member 19. Refrigerant medium will now be admitted to the outlet conduit 25 for flow through the conduit 8 into the evaporator 9. When the evaporator 9 has become flooded or wetted with refrigerant medium to a point adjacent the evaporator side of the bulb member 11, the cooling of the bulb member will permit the spring 22 to move the valve member 19 toward closed position. The expansion valve 6 will now function in the usual manner to throttle the flow of refrigerant medium to the evaporator 8, maintaining it flooded throughout its length. Any refrigerant medium which escapes from the outlet conduit 25 into the draw-off chamber 37 will be withdrawn by the compressor 1 through the equalizer passageway 41 and not be permitted to flow through the guide portion of the passageway 34 into the back pressure chamber 27. With extremely low evaporator temperatures, say in the neighborhood of 100° below zero F., the pressure change per degree change of temperature, is so small that frictional resistance, as by the usual packing, to the thrust member 35 would require a large temperature change in order to move the valve member 19.

Accordingly, it would be impossible to maintain a constant super-heat setting for the expansion valve, and refrigerant medium would be fed irregularly to the evaporator 9.

What is claimed and is desired to be secured by Letters Patent of the United States is:

A gas charged thermostatic expansion valve comprising a hollow casing having spaced suction pressure and valve chambers and having a straight passageway extending between and opening at its opposite ends through the adjacent end walls of said chambers, said casing having an annular guideway and closure portion extending into said passageway substantially in the plane of said suction chamber end wall, a diaphragm forming a wall of said suction chamber, a valve member in said valve chamber and controlling flow into said passageway, a thermostatic power element having a pressure chamber with the expansible wall thereof formed by said diaphragm, said power element having a feeler bulb containing a volatile liquid in limited quantity entirely condensable out of said bulb into said element pressure chamber, said casing having an inlet passageway leading to said valve chamber and having an outlet passageway from said straight passageway, means to warm said power element pressure chamber, a thrust rod extending longitudinally through said straight passageway and reciprocally guided in said annular portion and having its ends engaging said diaphragm and said valve member, an annular plug member surrounding said thrust rod adjacent said annular portion to provide a draw-off chamber therebetween and separating said outlet passageway from said draw-off chamber, a sleeve member slidably fitting said thrust rod within said draw-off chamber and seating on said plug member to close the clearance space between said plug member and said thrust rod, a helical spring surrounding said rod and held under compression between said sleeve member and said annular portion, said casing having an equalizer passageway opening directly into and through the side wall of said draw-off chamber, said annular portion fitting said thrust rod sufficiently closely so that suction pressure in said equalizer passageway will prevent refrigerant medium which escapes into said draw-off chamber from flowing into said suction pressure chamber.
